H. Holland,
Making Wooden Boxes.
Patented Apr. 13, 1832.

Harrison Holland

Letters Patent.)

The schedule referred to in these Letters Patent and making part of the same, containing a description in the words of the said Harrison Holland himself of his improvement in the machine for manufacturing Bones of Wood.

This machine consists of the parts, - 1° the frame supporting the machinery &c. 2° the machine itself on the gaging I. of the frame, this is made strong, of firm and solid materials, as in the model, occupying a space of about four by six feet square, and may be conveniently placed in a common shop room.

The frame may be better described, by considering it as consisting of a front and back part, the former supporting the auger and timber carriage - the latter the saw, and its frame & most of the machinery. - There are two distinct operations to be performed viz - cutting or boring out the box and sawing it off. And the frame is calculated to favour both of these operations.

The main or front part of the frame, is constructed and consists of the following viz - 1° a head plank three inches in thickness by six inches wide and four feet and three inches in height marked in the drawing A. 2° a foot plank of the same dimensions and corresponding with the head plank excepting as to length or height this being but three feet long marked B. - 3° two beams, five inches thick and six inches deep placed on opposite sides of the above mentioned planks, tenoned into the head plank, & receiving tenons on the upper end of the foot plank; in the model six feet long; they may be longer if necessary, both are marked C. -

4° a head block. this may be a two inch board plank, ten inches long by high resting on the beams, ten inches from the head plank, having a tongue extending down through, and below the beams, & confined at bottom by a key or wedge; this may be worn further

from or nearer to the head plank, if necessary, it is the main support of the auger, the mandrel of the auger passing through it nearly $\frac{1}{2}$, this is in two parts, the top part being removable to receive and screw on to confine the mandrel of the auger. - 3rd an ear, this is a solid piece of wood, two inches thick five inches wide at bottom & two at top, confined to the outer side of the front beam nineteen inches from the front head plank, running up nine inches above the beam. On the beam the timber carriage is called to distinguish it by and name. This in the model is five feet long but may be any given length to accommodate the length of the timber.

This is made of solid wood, two inches deep and five inches wide corresponding with the tops of the beam viz. such are the side pieces - these are tenoned ^{into} the head block and confined by ties, or rather connected by ties -

On each of these is fastened a cleat so as to form a groove on each side, in which a foot block is placed. The timber to be wrought is confined; the forward end in the head block for this purpose the timber should be square corresponding with a square cut out of the head block, the hind end is confined in the foot block and the foot block moves forwards, as the timber is shortened down by a weight and pulley, - A section is taken from the upper part of the head block, so as to form a square, this is hung by a joint at one end, and is made to press on the upper part of the timber, so as to confine it having teeth running into the timber. This has been called for distinction a vice, it acts on the principle of a lever, and the power applied is a weight suspended from the other end. All the parts of this carriage as well as of the whole machine will be understood by inspecting the model.

The back part of the frame is firmly united with the other part. The back side consists of what may be called a side plate and the posts. The posts are tenoned at each end. The outer posts correspond with the head and foot planks in the front frame, the middle post is one foot from the front post. The size of

Apr. 13, 1832

the timber, three inches square. The tie marked C. This tie is fast to the front part of the frame by ties, entering each part by a tenon and into the head and foot, blanks, and an inner post, standing under and supporting the inner beam and parallel with the middle post.

These ties are three inches thick and six inches deep big. The lower or tie marked D, made substantial in order to support part of the machinery. — There are also three ties near the top, the first six inches from the head plate, the second eighteen further and the third eighteen inches further still, united to the inner beam by tenons, the upper part projecting and rising as high as the timber carriage; all these ties two feet in length between joints and the upper tie marked E, on the two front upper ties is placed the law carriage tie, four inches long and seventeen inches wide, the timber two inches wide and two and one half inches deep firmly united together by ties near each end. — Between the last mentioned tie parallel with the sides of the frame is a cross tie of the same size having a row of cog wheels inside uniting with the wheel which carries the law frame or carriage.

On the fore part of this carriage are placed blocks or poppet heads in which the axle of the law runs. the law carriage marked H .... II of the machinery or gearing, this consists of the following parts viz. — The driving pulley marked I eighteen inches in diameter projecting at the head of the machine.

2. the first drum three feet in diameter one foot in length running between the first and second lower ties connecting the two lower parts of the frame, and on the same axle with the driving pulley marked J. this carries the bands propelling both the auger and law, and also the second drum.

3. the second drum three feet long two feet in diameter marked K on the head end is a cog wheel twenty inches in diameter with one hundred and forty cogs, dipping into a small wheel, one inch and one half in diameter, with ten cogs, and on the axle of the driving pulley between the two drums.

Apr. 13, 1832

this small wheel communicating motion to the second drum.

On the board of this drum, near the head, is a cog one thousand six
viz of sufficient length to carry the saw carriage as far forward as
necessary, also a groove near the center three quarters of an inch
deep described in form of the elliptic, in which plays a cog near
the end of the lever hereafter described in such a manner that
the revolution of the Drum move forward and back the timber
carriage as desired. There is also near the lower end of this drum
one cog whose office is to assist in drawing back the saw carriage
it. a semi cog wheel fourteen inches in diameter and two inches
thick, running on an axle, whose pivot are fixed in the two front
upper bars, on whose axle also is a small cog wheel under the saw
carriage communicating with and running in the cog on the lower
side of the saw carriage above named, these latter cogs move up the
saw carriage, the semi cog wheel receives its motion from the cog
on the second drum.

3rd The timber carriage, this is carried forward and back as
in course of the operation it becomes necessary in order to bring the
timber to be wrought in contact with the auger and to withdraw
it when also it is necessary, . . . This is done by means of a lever
which may be a hard piece of timber six inches in thickness by
four and four inches wide in the centre reduced about one half
at each. This lever hangs and plays on a bolt, on the
lower side of the inner beam, near its center, one end is
fastened to the front side of the carriage by means of a strap
of iron & bolt attached to the side of the carriage bending
down as low as the lower side of the front beam, the other
end has a cog in it playing in the elliptical groove around
the second drum this groove is so designed as to apply the
power to that end of the lever, in carrying forward and back
the carriage as above, the lever playing on the bolt first
above mentioned at its fulcrum this lever reaches to,

4th The saw which is circular in common form ten inches

Apr. 13, 1832.

in diameter, & of iron with a pulley on the same of the proper size and proportion. --- of the auger, this is a screw auger without a centre, this is claimed as a new invention and may be usefully applied to other uses. the length and size will be determined by the size of the machine & the box.

The mandrel of the auger must be at least one half inch greater in diameter, than the auger in order to receive two cutters, one opposite to the other, these are dovetailed into the head of the mandrel & brought to an edge so as to cut and smooth the outside of the box, there is a pulley on the mandrel & the bands which may be of leather or chain running on a cog.

III. The operation

The power is applied to the driving pulley, this puts the whole in operation, this communicates motion to the first drum & also to the second drum, the first drum giving motion to the auger and saw, the second to both the carriages, it moves them up and back. The timber carriage is moved by means of the lever described above & the timber in the carriage is moved in this way viz. when the auger has done its work, and the carriage begins to draw back a pin in the end of the rap called for destruction the vice in the head block of the timber carriage over and confining the timber pressing over a slide like the latch of a door being in the inner side of the car which raises the same and leaving the timber free, the head block of the carriage, drawn by the pulley and weight described above then drives the timber forward till this last or vice drops and holds it from again, but least the timber should be pressed too far forward to the lower side of the carriage, is fixed an arm of iron, at the end of which near the auger and at the right angle is fixed a piece of wood thin and like a hand playing up and down in mortise of iron projecting forward of the head block, so as to rise forward of the timber and prevent its going too far. This is raised up by a vice again the iron passing at the right time over a slide similar to the

6997X

above fastened to a block projecting in the inner side of the inner frame. The elliptical circle or groove in the wood drum in which the cog plays, on the end of the last wheel, as the power to move the timber carriage forward and back as required, the saw carriage is moved forward by the small wheel on the side of the carriage wheel, the same down communing motion to the carriage wheel & this by means of the cog under the middle piece of the carriage and the small wheel just mentioned the carriage is pushed forward bringing the saw to the timber after it has performed its work and the cog sawed off. the carriage is pulled back again to make way for the cutting operation by the auger by means of a lever turning on a pivot at its centre is a fulcrum resting on the plate one end attached to the hinder part of the carriage the other to a reach, & the reach being on a cross, passing through the third upper tier down to the second drum & then turned by means of the cog on the same this is graduated as performed so as to have this done the saw and carriage back just in time.

Remarks. 1. The dimensions and proportion above mentioned are assumed as proper and yet they may be varied if necessary, 2. boxes of different sizes may be made by this machine, 3. the lids may be made in the same way, the auger however may be proportionately shorter and the slide moved proportionately nearer the head of the carriage, 4. boxes may be prepared for the lid by sliding them on to the mandrel of a common turning lathe and gauging the cutting tool or turning chisel having the same in such shape as desired. 5. the power may be applied by water or steam or any adequate power. — 6.

The timber to be worked should be sawn square of the size of the box, and may be as long as the carriage will admit. Green timber is equally good as that which is seasoned.
